UNITED STATES PATENT OFFICE.

MAXIMILIAN LUDWIG MUELLER, OF SCHANDAU, SAXONY, GERMANY.

ADVERTISING-LID FOR BEER-GLASSES.

SPECIFICATION forming part of Letters Patent No. 396,224, dated January 15, 1889.

Application filed March 12, 1888. Serial No. 267,052. (No model.)

To all whom it may concern:

Be it known that I, MAXIMILIAN LUDWIG MUELLER, a subject of the King of Saxony, and a resident of Schandau, Saxony, Germany, 5 have invented a new and useful Advertising-Lid for Beer-Glasses, &c., of which the following is a specification.

This invention relates to covers or lids for beer-glasses, drinking-cups, or the like; and 10 it consists in a cover of improved construction, suitable for the display of advertisements.

Referring to the accompanying drawings, Figure 1 is a vertical section of a goblet with 15 loose cover, the cover being closed and placed on the goblet. Fig. 2 is a vertical section showing the cover opened for insertion or removal of sheets or leaves containing advertisements. Fig. 3 is a plan view of the closed cover. 20 Fig. 4 is a vertical section of a modification, in which a central cross-bar replaces the hinged cover and the device holding the advertisement-sheets is detachable. Fig. 5 is a plan view thereof.

25 The cover consists, essentially, of a plate, D, of size and shape required to cover the respective cup or glass. On this cover is fixed a removable or stationary pin, K, upon which the advertisement-sheets are held, and which 30 may serve as a hinge or pivot to the latter.

To hold sheets upon the pin, a cover, C, is provided, which, as in Fig. 1, may be a whole cover hinged and folding onto flanges B at the edge of the plate D, and having a central 35 glass window, a, or may be a bar hinged or connected to the cover and extending across the sheets onto the end of the pin K.

In Fig. 4 the plate C is made with the plate z out of one piece of metal bent round so as 40 to form a V-shaped spring-bow, one arm of which is the plate C and the other arm the plate z. The latter is flat to lie upon the top of the lid D, and on its under surface are made the tongues h h, engaging in the slots 45 i i in the cover, and holding the V-clip in place. In this case the pin K is fastened on the

upper side of the plate z, and projects upward into or through a slot in the plate C. On the pin K is pivoted a number of advertising-disks adapted to be folded together 50 under the plate C and normally held in such position by a depression, t, or equivalent, in or under the plate C.

I claim—

1. A cover for goblets, beer-glasses, and the like, comprising, in combination, an under plate, D, forming a cover to said goblet or the like, a pin, K, thereon, adapted to receive advertising-sheets, and a plate, C, adapted to cover and retain said advertising-sheets. 60

2. A cover for goblets, beer-glasses, and the like, comprising, in combination, an under plate, D, forming a cover to said goblet or the like, a pin, K, thereon, adapted to receive advertising-sheets, and a cover-plate, C, attached 65 to said plate D and projecting over said pin K, so as to hold the sheets thereon, substantially as set forth.

3. The combination, with a plate, D, adapted to form a cover to a goblet, beer-glass, or the like, of slots in said plate, a plate, z, tongues on said plate z, engaging in said slots, a projecting pin, K, on said plate z, and a plate, C, integral with said plate z, and extending over the same and over the said pin K, substantially as and for the purpose set forth. 75

4. The combination, with a plate, D, adapted to form a cover to a goblet, beer-glass, or the like, of slots i in said plate, a spring-bow formed, substantially, by two parallel plates, z 80 C, tongues H on said plate z, adapted to engage in said slots i, a pin, K, projecting from said plate z, and a recess, t, in the plate C, adapted to cover said pin, substantially as and for the purpose set forth. 85

In testimony whereof I have signed this specification in the presence of two subscribing witnesses.

MAXIMILIAN LUDWIG MUELLER.

Witnesses:

ADOLPH PRAETORIUS,
C. BARTHOLAMAY.
